UNITED STATES PATENT OFFICE.

WILLIAM EDWIN RUSSELL AND WILLIAM EARLE RUSSELL, OF DANBURY, CONNECTICUT, ASSIGNEES, BY MESNE ASSIGNMENTS, TO LOVELL-McCONNELL MANUFACTURING CO., A CORPORATION OF DELAWARE.

ALARM-HORN.

1,120,627.

Specification of Letters Patent.

Patented Dec. 8, 1914.

Application filed December 15, 1910. Serial No. 597,493.

To all whom it may concern:

Be it known that we, WILLIAM EDWIN RUSSELL and WILLIAM EARLE RUSSELL, both citizens of the United States, residing in the 5 city of Danbury, county of Fairfield, and State of Connecticut, have invented certain new and useful Improvements in Alarm-Horns; and we do declare the following to be a full, clear, and exact description of the 10 invention, such as will enable others skilled in the art to which it appertains to make and use the same.

Our invention relates to alarm horns such as are used on automobiles, boats, and in 15 other instances where it becomes necessary to sound a signal, and has for its object to provide an exceedingly efficient device of this description without the use of rigid or unyielding elements such as cams heretofore 20 employed for the purpose of positively displacing a sounding diaphragm preparatory to the resilient recovery of the latter.

With these ends in view our invention consists in certain details of construction 25 and combination of parts hereinafter fully described and then particularly pointed out in the claims which conclude this description.

In the accompanying drawing Figure 1 is 30 an elevation, partly in section, illustrating our improved horn; Fig. 2 an elevation of the disk or diaphragm which we employ, and Fig. 3 an interior end view showing particularly the rotary head carried by the shaft of the motor.

Similar numerals of reference denote like parts in the several figures of the drawing.

Our improvement is operated by any suitable and approved motor which may be actuated by electricity or by any other agent, 40 although we prefer to operate the same by an electric current since the latter may be very readily and simply controlled by merely closing and opening the circuit, but our improvement has nothing whatever to do with any construction of motor and we 45 therefore have not illustrated nor will we describe such motor.

Heretofore, in the construction of alarm 50 horns, a sounding diaphragm has been employed which has been vibrated in various ways, such as by a rotary cam acting to rigidly force the diaphragm outwardly so

that after the cam surface has left the diaphragm the latter will by its resiliency recover and thereby complete the vibration; also the diaphragm has been vibrated directly or indirectly by the make and break principle due to the agency of an electromagnet. In the illustrated embodiment of 55 our invention the resultant sound is due in part to the vibration of the diaphragm and in part to violent and rapid disturbances of the air by means of piston-like impulses of the air through openings in the diaphragm. 60

1 is a casing containing any suitable motor 2 (not shown in detail) and 3 is the shaft of said motor projecting beyond the face thereof within any suitable hollow cheek plate 4 that is secured to said casing. 70

5 is a head which is preferably circular in cross section and is secured to and carried by said shaft, and within this head are open pockets or recesses 6 that are concentrically disposed with respect to the axis of revolution of said shaft. Contained freely within the mouths of these pockets are balls 7 which are backed by coil springs 8 that are confined between the inner walls of said pockets and the rear of said balls, the function of 75 said springs being to normally project or impel said balls outwardly.

9 is the horn or resonator whose base portion 10 is secured to the plate 4, and 11 is a diaphragm or disk which is confined at its 80 outer edge between said plate and base. This diaphragm has perforations or recesses 12 that are disposed concentrically with respect to the axis of revolution of the shaft 3 and that coincide with the balls 7 as the 85 head 5 is revolved, so that when the rotor turns slowly it may be clear that these balls will track against the diaphragm until they come opposite the perforations into which latter they will be violently forced by the resiliency of the diaphragm and the action of the 90 springs 8. The outer face of the head 5 is normally spaced from the diaphragm so that it will be readily understood that the body of air within the hollow cheek plate 4 will be in 95 communication with the outside atmosphere through the medium of this space and the perforations in the diaphragm. We prefer to utilize four of these balls 7 contained within four pockets 6 in the head 5 and four 100 perforations 12, so that as the head 5 is re-

volved the balls will operate to sequentially open and close these perforations, but while we prefer this construction we do not wish to be limited thereby since results more or less satisfactory may be obtained by increasing or decreasing the number of these perforations as well as the number of the balls, but we have ascertained that exceedingly good results will follow in the instance of the 5 construction shown in the drawings. The diameter of the balls is greater than that of the perforations so that, as the head is revolved, the balls will effectively plug the perforations without passing through the 10 same.

In the drawing we have shown the pockets 6 inclined or diverging from their inner ends toward the periphery of the head 5, since the balls are thereby initially affected 15 by centrifugal force to the extent that the alarm is more pronounced as the motor is acquiring headway than would be the case in the instance of straight pockets parallel to the motor shaft. It is not absolutely 20 necessary to utilize the springs in connection with the divergent pockets since the balls will be projected beyond the pockets both by gravity and centrifugal force and will be held by the latter in operative position, and while we prefer to use the springs 25 we do not wish to be limited thereby except in the instance of pockets that are parallel to the motor shaft.

When the pockets are divergent, the 30 silency of the diaphragm, when the motor has acquired speed, is opposed solely by the centrifugal force which binds the balls against the walls of the pockets, and while the balls will yield a trifle nevertheless they 35 will be instantly projected as soon as they come opposite a perforation of the diaphragm, and thus it will be understood that the impulses given to the air as above referred to are due to the combined and mutual movements of the diaphragm and balls 40 toward each other. The springs are merely serviceable in insuring the proper projected position of the balls so that they can be acted on by the centrifugal force at the 45 earliest possible moment in order to make the initial alarm louder and more sustained. It is of course possible to make the springs powerful enough so that the centrifugal force will not become a factor at all, but this 50 would not only greatly increase the wear against the diaphragm and balls but would consume power uselessly, and we would greatly prefer to rely on the centrifugal force supplemented by the auxiliary springs 55 to bring the balls more quickly into effective 60 operation.

The force of the springs impels the balls into initial contact against the diaphragm with force sufficient to slightly bow the latter outwardly, and as the head 5 revolves

these balls will bind with more or less friction against the outer side walls of the pockets 6, thus rendering it more difficult to force the balls rearwardly, and as the speed of the motor increases this friction will become 70 greater and the result is that the balls will be held against return movement into their sockets by sufficient force to cause the diaphragm to be vibrated outwardly to a greater degree as shown in dotted lines in 75 Fig. 1. It follows therefore that these balls will rapidly and violently strike glancing blows at the far sides of the perforations in the diaphragm and will impart a series of rapid pulsations or vibrations to the diaphragm. It is not necessary, therefore, to utilize a diaphragm having such a high degree of elasticity since we do not depend solely upon the vibrations of such diaphragm to cause the greater volume of 80 sound. The balls are perfectly free, and in engaging with the diaphragm they will have an independent revolution after the manner of ball bearings, and this peculiarity is a great benefit because we are thereby enabled 85 to greatly economize in the use of power. It will thus be seen that we do not rely solely upon the positive vibrations of the diaphragm nor do we employ rigid unyielding elements as the cams in order to force 90 the diaphragm outwardly and then permit it to complete its vibrations.

We prefer that the head shall be of such dimensions that it will be coextensive with that part of the area of the diaphragm 100 which contains the perforations and is coincident with the orbit of said head, so that said perforations will at no time have more open communication with the body of air contained within the cheek plate 4 than that 105 afforded by the space between the diaphragm and the head itself.

Having thus described our invention what we claim as new and desire to secure by Letters Patent is:—

1. An alarm horn, comprising a horn or resonator, a diaphragm having perforations, a rotary head spaced from said diaphragm and carrying means for sequentially plugging and opening said perforations.

2. An alarm horn, comprising a horn or resonator, a perforated diaphragm, and a rotary plunger element maintained in contact with said diaphragm and adapted to alternately plug and open said perforations.

3. An alarm horn, comprising a horn or resonator, a perforated diaphragm, a motor, an element revolved by said motor in spaced relation to said diaphragm, and plunger devices carried by said element and co-operating with said diaphragm to alternately plug and open said perforations.

4. In an alarm horn, the combination of a horn or resonator, a diaphragm having concentric perforations, a motor, and guided

plunger devices carried by said motor against said diaphragm and coincidently concentric with said perforations.

5. In an alarm horn, a horn or resonator and a perforated diaphragm, in combination with rotary resiliently acting plungers maintained in contact with said diaphragm and adapted to alternately plug and open the perforations therein.

10. 6. An alarm horn, comprising a horn or resonator, a perforated diaphragm, a rotary recessed head in close relation to said diaphragm, and spring impelled balls contained within the recesses in said head and adapted to track against said diaphragm and plunge within the perforations therein.

15. 7. An alarm horn, comprising a horn or resonator, a diaphragm, a rotary head having open pockets in its face and spaced from said diaphragm, balls loosely contained within the mouths of said pockets, and springs within said pockets and bearing against said balls at the rear thereof whereby the latter may advance or recede in respect to said diaphragm.

20. 8. An alarm horn, comprising a horn or resonator, a rotary head having open pockets in its face that are divergent to and concentric with the axis of revolution of said head, balls freely contained within said pockets, and a diaphragm spaced from said head and having surface irregularities which are concentrically arranged with respect to the axis of revolution of said head and successively engaged by said balls.

25. 9. An alarm horn, comprising a horn or resonator, a rotary head having open pockets in its face that are divergent to and concentric with the axis of revolution of said head, balls freely contained within said pockets, springs within said pockets and bearing against the rear of said balls, and a diaphragm spaced from said head and having surface irregularities which are engaged by said balls as said head revolves.

30. 10. In an alarm horn, the combination of a horn or resonator, a diaphragm having a concentric row of perforations therein, a motor, a head spaced from said diaphragm and carried by said motor and coextensive with that part of the diaphragm which contains said perforations and is coincident with the orbit of said head, open pockets in the face of said head that are disposed divergent to and concentric with the axis of revolution of said head and are coincidently concentric with said perforations as the head revolves, balls freely contained within said pockets, and springs likewise within said 35 pockets in the rear of said balls and acting to initially force the latter in contact against said diaphragm.

35. 11. In a device of the character described the combination with a recessed diaphragm, a resonator therefor, and means for striking

said diaphragm at said recess a plurality of successive glancing blows.

12. In a device of the character described the combination with a recessed diaphragm, a resonator therefor, and rotatable means 70 for striking said diaphragm at said recess a plurality of successive glancing blows.

13. In a device of the character described the combination with a recessed diaphragm, a resonator therefor, and centrifugally controlled means for striking said diaphragm at said recess a plurality of successive glancing blows.

14. In a device of the character described the combination with a recessed diaphragm, 80 a resonator therefor, and centrifugally controlled rotatable means for striking said diaphragm at said recess a plurality of successive glancing blows.

15. In a device of the character described 85 the combination with a recessed diaphragm, a resonator therefor, and centrifugally controlled means for striking said diaphragm at said recess a plurality of successive glancing blows.

16. In a device of the character described 90 in combination with a recessed diaphragm, of an impact device to strike said diaphragm at the edge of said recess.

17. In a device of the character described, the combination with a diaphragm, a motor, 95 an armature for said motor, a ring carried by said motor having a plurality of recesses, and balls carried in said recesses and actuated by centrifugal force when said motor is operated, whereby said balls are adapted to 100 strike said diaphragm.

18. In a device of the character described, the combination with a recessed diaphragm, means for striking said diaphragm at said recess a plurality of successive glancing 105 blows, and a motor for operating said means.

19. In a device of the character described the combination with a recessed diaphragm, means for striking said diaphragm at the far side of said recess a plurality of successive glancing blows and a motor for operating said means.

20. In a device of the character described, the combination with a diaphragm having a plurality of recesses, and means for striking 110 said diaphragm at all of said recesses simultaneously.

21. In a device of the character described the combination with a diaphragm, and a plurality of centrifugally controlled independently rotatable impact devices for simultaneously striking said diaphragm at a plurality of separate points adjacent to but distributed about the center.

22. In a horn or signalling device the combination of a vibratory sound producing part in the form of a diaphragm, and a rotary part for imparting vibrations to said diaphragm and having its axis of rotation presented endwise to the plane of said dia- 125

65. 130

phragm, one of said parts having a row of circular recesses arranged concentrically with the axis of rotation and the other of said parts having a rotatable ball carried thereby and mounted for engagement with said recesses in succession as said second-mentioned part rotates about its axis.

23. In a horn or signaling device the combination of a vibratory part in the form of a diaphragm, and a rotary part including a high-speed drive shaft substantially at right angles to the plane of the diaphragm, and a head adjacent to and spaced from said diaphragm, one of said parts presenting an annular row of circular recesses in the face thereof toward the other part and a ball supported by the other part, each of said last mentioned recesses being of less diameter than said ball and adapted to successively receive said ball during the rotation of said second-mentioned part to cause the vibration of the diaphragm.

24. A device of the character described comprising an agitator member including a motor-driven rotary disk, a vibratory member mounted adjacent thereto but spaced therefrom, and a transmitter member operating between said agitator member and said vibratory member and normally resting in a depression in one of said members and held therein solely by the other of said members, said last-mentioned member having a series of depressions with which said transmitter member successively engages during the rotation of said disk.

25. A device of the character described comprising an agitator member consisting of a motor-driven rotary disk having a series of recesses in its face, a vibratory-member mounted adjacent thereto but spaced therefrom and having a series of recesses and a series of hardened steel balls mounted in the recesses of one of said members and adapted for successive engagement with the recesses of the other of said members during the rotation of said disk.

26. A device of the character described comprising an agitator member consisting of a motor-driven rotary disk, a vibratory member mounted adjacent thereto but spaced therefrom, and a transmitter member normally resting in a depression in one of said members and held therein solely by engage-

ment with the other of said members, said last mentioned member having a series of depressions successively engaging with said transmitter member during the rotation of said disk.

27. A horn or signaling device including a diaphragm, a rotor in the form of a head rotatable about an axis at right angles to said diaphragm and having a series of recesses in the face thereof toward said diaphragm, and an annular row of hardened steel balls mounted for engagement with said diaphragm to vibrate the latter and free to move in a direction substantially at right angles to said diaphragm during the rotation of said rotor.

28. A horn or signaling device including a diaphragm, a rotor in the form of a head rotatable about an axis at right angles to said diaphragm at the center thereof and having a series of spaced recesses in the face thereof toward said diaphragm, and an annular row of hardened steel balls mounted for direct engagement with the surface of said diaphragm to vibrate the latter and free to move in a direction substantially at right angles to said diaphragm during the rotation of said rotor.

29. In a horn or signaling device, the combination of a vibratory sound producing part in the form of an elastic diaphragm, a rotary part for imparting vibrations to said diaphragm and having its axis of rotation presented endwise to the plane of said diaphragm, a high speed electric motor for rotating said second mentioned part, one of said parts having a series of surface irregularities arranged concentrically with the axis of rotation and the other of said parts having a socket and a rotatable ball positioned therein, said ball engaging with said series of irregularities in succession as said second mentioned part rotates and said ball being held in said socket solely by engagement with the opposed part.

In testimony whereof we affix our signatures in presence of two witnesses.
